UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-SEAT.

1,281,793.

Specification of Letters Patent. Patented Oct. 15, 1918.

Application filed March 2, 1915. Serial No. 11,511.

To all whom it may concern:

Be it known that I, GEORGE B. KOHLER, a citizen of the United States, residing in Philadelphia, Pennsylvania, have invented 5 certain Improvements in Car-Seats, of which the following is a specification.

One object of my invention is to improve the construction of the seats of railway cars of the type in which the back can be shifted 10 from one side of the seat to the other and in which the seat section is tilted to correspond to the position of the back.

A further object of the invention is to make the parts of the seat, particularly the 15 moving parts, suitable for manufacturing out of pressed steel.

A still further object of the invention is to dispense with machine work in preparing the parts for assembling.

20 Another object of the invention is to increase the strength and rigidity of the moving parts and to reduce the weight of the seat.

These objects and other advantageous ends 25 I attain in the following manner, reference being had to the accompanying drawings, in which:

Figure 1 is a longitudinal sectional view of sufficient of a car seat to illustrate my invention, the seat, in the present instance, being 30 of the type which is provided at one end with a wall bracket and at the other end with a pedestal.

Fig. 2 is an end view of my improved car 35 seat;

Fig. 3 is a sectional view on the line $a-a$, Fig. 2, drawn to an enlarged scale, showing the back section in the mid position;

Fig. 4 is a part section on the line $b-b$, 40 Fig. 2;

Fig. 5 is a sectional plan view on the line $c-c$, Fig. 2;

Fig. 6 is a detached perspective view of one of the rockers;

45 Fig. 7 is a detached perspective view of one of the back frames;

Fig. 7^a is a detached perspective view of the cap plate for a back frame;

Fig. 8 is a detached perspective view of 50 one of the bearing plates secured to the body portion of the car seat;

Fig. 9 is a perspective view of the end plate;

Fig. 10 is a perspective view of one of

the seat back levers, showing the bushing detached;

Fig. 11 is a perspective view of one of the seat back links;

Fig. 12 is a detached perspective view, showing one of the devices at the wall end 60 of the seat to prevent the lifting of the rocker;

Fig. 13 is a perspective view of a device similar to that illustrated in Fig. 12, and to which is secured the end plate at the aisle 65 end of the seat;

Fig. 14 is a sectional view through one of the pivots;

Fig. 15 is an enlarged sectional view of 70 one of the back frames;

Fig. 16 is an inverted sectional plan view on the line $d-d$, Fig. 15;

Fig. 17 is a longitudinal sectional view of 75 one of the seat back levers;

Fig. 18 is a longitudinal sectional view of one of the seat back links;

Fig. 19 is a longitudinal sectional view of 80 the end plate on the line $e-e$, Fig. 20;

Fig. 20 is a sectional view on the line $f-f$, Fig. 19, and

Fig. 21 is a sectional view showing one of 85 the stops for the back section.

Referring to the drawings, 1, 1 are the two longitudinal angle bars which connect the end bearing plates 2 and 3. The seat 85 structure, in the present instance, is supported at the wall side of the car 5, as shown by dotted lines in Fig. 1, by a bracket 4, which is secured to the side and extends under the seat structure and is fastened thereto by 90 bolts 6, which also secure the bars to the end bearing plate. The bearing plate at the aisle end of the seat is secured to the bars by bolts 6^a.

7 is the pedestal which is located under 95 the car seat some distance from the aisle end thereof and is secured to the bars 1, 1, as shown in Figs. 1 and 2. Each bearing plate 2 and 3 has a lip 8 at each end thereof which extends back of the bars 1 and aid the bolts 100 in holding the structure rigidly in position. 9 is the seat section and 10 is the back section. The seat section 9 rests upon rockers 11, as shown clearly in Fig. 6, and pins 12 on these rockers extend into the openings on 105 the underside of the seat so as to prevent the seat from moving independently of the rockers. The rockers rest upon the edges

of the bars 1 and have flanges 13 which are cut away at 14. Plates 15 and 16 are secured to the ends of the structure and have tongues 17 and 18, respectively, Figs. 12 and 13, 5 which extend over the flanges 13 of the rockers so that the rockers are prevented from lifting by these tongues, as clearly shown in Fig. 4.

Secured to the back section 10 are the arms 10 19, preferably made of pressed sheet steel in the form illustrated in Fig. 7, and bearings 20, 21 and 22 are pressed from this sheet, as illustrated in the drawings, so as to force the raw edge of the metal away from 15 the bearing point, thus dispensing with machining. A cap plate 23 is secured to each arm 19, as illustrated in Fig. 7. This cap plate not only covers the opening 20, but also acts as a reinforcement for the arm at the 20 joint or weak point. The cap plate has side extensions 25 which inclose the gap at the pivot rod 24, as the back of the seat structure is less in width than the seat cushion.

Each plate 2 and 3 has three bearings 26, 25 27 and 28. These bearings are pressed as are the bearings 20, 21 and 22, and are for the same purpose. There is a seat back lever 29, Fig. 10, at each side of the seat structure and this has an extended bearing 30 formed by shaping the metal by pressing. This bearing 30 journals in the bearing 20 of the back frame 19. Within this bearing is a bushing 31 in which the pivot rod 24 is mounted and this bushing extends into the 35 opening in the bearing 20 of the back frame 19 and the seat back lever is pinned to the pivot rod. This pivot rod 24 extends from one side of the back to the other so that any motion given to the mechanism on one side 40 of the seat will be transmitted to the mechanism on the other side without straining the back of the seat. The lower portion of the seat back lever 29 is pressed into shape, as shown in the drawings, to form a bearing 45 32 which fits over the bearing 26, as illustrated in Fig. 14, and a rivet 33 having a wide head fastens the two parts together, as clearly illustrated in said figure.

34, 34 are the seat back links, two on each 50 side, which have bearings 35 and 36 fitting respectively the bearings 21, 27, and 22, 28 of the back frame 19 and the bearing plates 2 and 3. The parts are shaped as illustrated in Fig. 14, and are also connected by rivets. 55 These two links are slightly out of parallel with each other so as to guide the back section and hold it in the proper inclined position. On each seat back lever 29 is an extension 37 having a pin 38 which enters a 60 slot 39 in each rocker 11 so that, when the back section is shifted from one side of the structure to the other, the rockers will be moved correspondingly in order to give the seat section the proper tilt with respect to 65 the back.

In the present instance, I provide an end plate 40 which covers the mechanism including the links and lever and this end plate is made hollow and in two sections. The inner section 41 is flanged and the outer section 42 70 is also flanged. The flange of the outer section extends over the flange of the inner section and is notched at 43 to receive the edge of the flange of the inner section, so that the two parts are held rigidly in position when 75 the flange of the outer section is beaded over the flange of the inner section, as clearly shown in Figs. 4 and 9. The inner section 41 is recessed at 44 and in the base of each recess is a slot 45, the slot being wider at 80 the upper end than at the lower end. The bracket plate 15 has an upright portion 46 and a tongue 47 is bent from this upright portion and extends into the wide portion of the slot 45 and a bolt 48 extends through 85 a hole in the upright portion 46 of the bracket plate and also through the narrow portion of the slot 45, as clearly shown in Fig. 4, holding the end plate firmly to the structure. The tongue also acts as a lock 90 for the head of the bolt and keeps it from turning.

This particular seat is of the wall type and rests on a bracket, as described above, but it will be understood that if the seat be 95 clear of the wall, then a pedestal, and, preferably, an end plate, may be secured to the wall end of the seat structure.

It will be noticed that the lower end of each seat back frame 19 has two notches 49, 100 Fig. 7, and the portions 50 of the bracket plates 15 enter the notches, Figs. 2 and 21, and act as a stop for the back section when it is shifted to either of its two extreme positions.

In securing the several pivoted sections together, I use a rivet with a large head, as illustrated in the drawings, and the body portion of this rivet is pressed out as clearly shown in Fig. 14, firmly holding the parts 110 together, but it will be understood that a bolt, or other fastening device, may be substituted for the rivet.

It will be seen from the above description that I am enabled to make all of the metallic 115 portions of the seat from pressed steel or equivalent metal. The parts are light and no machining is required after the elements of the structure leave the press. The bearings are substantial and one bearing snugly 120 fits another. The parts can be attached by rivets, since the strain is taken by the ribs or flanges around the bearings instead of by the rivets themselves. As the parts are made from pressed sheet steel they are 125 interchangeable and repairs can easily be made without the aid of a skilled mechanic.

I claim:

The combination in a car seat, of a pair 130 of longitudinal bars; end bearing plates se-

cured to the ends of said bars and forming, with the latter, a supporting structure, each of said plates having three bearing portions formed thereon, the center bearing portion being above the other two portions; a back section; seat back frames secured to the back section at each end thereof, each of said frames having three bearings thereon, the center bearing being above the other two 5 bearings; a seat back lever at each end of the structure and mounted upon the center bearings of the end bearing plates and the seat back frames; a movable seat engaged by said 10 back lever; and a pair of seat back links at each end of the seat structure and mounted upon the outside bearings of the end bearing plates and the seat back frames and offset laterally in respect to the plane of movement of the seat back levers. 15

In testimony whereof I have signed my name to this specification in the presence of two subscribing witnesses.

GEORGE B. KOHLER.
